UNITED STATES PATENT OFFICE.

ARTHUR R. HAVENER OF WALTHAM, MASSACHUSETTS, ASSIGNOR TO AMERICAN LACING HOOK CO., A CORPORATION OF NEW JERSEY.

MACHINE FOR SETTING LACING-HOOKS IN THE UPPER OF A BOOT OR SHOE.

1,090,103.

Specification of Letters Patent. Patented Mar. 10, 1914.

Application filed November 25, 1912. Serial No. 733,253.

To all whom it may concern:

Be it known that I, ARTHUR R. HAVENER, a citizen of the United States, residing at Waltham, in the county of Middlesex and State of Massachusetts, have invented new and useful Improvements in Machines for Setting Lacing-Hooks in the Upper of a Boot or Shoe, of which the following is a specification.

10 This invention relates to an improved mechanism for setting lacing hooks in the uppers of boots and shoes and is an improvement upon the machine of the invention of Arthur R. Havener patented November 29, 15 1910, No. 977,909.

The object of the invention is to provide a machine of the character set forth in which an organized mechanism for setting lacing hooks in the uppers of boots and shoes is supported upon a frame, the frame itself being hinged to a base so that said frame and its organized mechanism may be tipped at an angle to the base to allow the different parts of the mechanism to be readily accessible, especially the parts attached to and connected with the main driving shaft of the machine, while upon the base is mounted mechanism to operate the clutch mechanism and also to operate, preferably simultaneously, the means whereby the presser foot is moved toward or away from the work-support.

It is the object of this invention still further to provide an improved and convenient mechanism for varying the feed of the upper, so that the punch will feed the upper from a certain given point different distances and thus vary the space between the lacing hooks, this improved mechanism being so arranged and constructed that it can be quickly and accurately changed.

The invention consists in the combination and arrangement of parts set forth in the following specification and particularly pointed out in the claims thereof.

45 Referring to the drawings: Figure 1 is a front elevation of my improved lacing hook setting machine partly broken away to save space in the drawings. Fig. 2 is a side elevation of the machine, also partly broken away and viewed from the right of Fig. 1.

Fig. 3 is a sectional elevation taken on line 55 3—3 of Fig. 2. Fig. 4 is a detail sectional elevation taken on line 4—4 of Fig. 3. Fig. 5 is a sectional elevation taken on line 5—5 of Fig. 1, as viewed from the left of said figure. Fig. 6 is a sectional elevation of 60 the clutch taken on line 6—6 of Fig. 2.

Like numerals refer to like parts throughout the several views of the drawings.

In the drawings, 10 is the frame of the machine and 11 the base. Said frame is 65 pivoted or hinged to the base 11 at 12 and is fastened to said base in order that it may not tip upon said pivots by screws 13, 14 which extend through ears 15, and 16, respectively, on the frame 10 and have screw- 70 threaded engagement with ears 17 and 18, respectively, on the base 11. Thus the frame is fastened firmly to the base.

The main driving shaft 19 is journaled in bearings 20 and 21 on the under side of 75 the frame 10 and is rotated by a clutch pulley 22 journaled to rotate upon the main driving shaft 19 and adapted to be locked to said shaft by the clutch member 23. The clutch pulley forms one member of the 80 clutch mechanism and the part 23 forms the other member. The part 23 is keyed to the shaft 19.

A locking dog or arm 24 is pivoted to the member 23 and when in the position illustrated in Fig. 6, that is, with the tripper slide 25 in engagement therewith, said locking dog allows the clutch pulley 22 to rotate freely without rotating the shaft. When, however, the tripper slide is withdrawn from engagement with the locking dog 24, said locking dog is immediately thrown outwardly at its free end by the spring 26 and is then engaged at the shoulder 27 thereon by one of the clutch teeth 95 28. The two members of the clutch 22 and 23 are then locked together and the rotation of the pulley in the direction of the arrow thereon causes the member 23 to be rotated in the direction of said arrow together 100 with the shaft 19 to which it is fastened.

When the machine is at rest and the operator is placing an upper in position to have a lacing hook set therein, the pulley 22 is free to rotate on the shaft 19 and the trip- 105

per slide 25 is in engagement with the locking dog 24. The tripper slide 25 is moved to engage the locking dog 24 by a spring 29 and is moved in the opposite direction to disengage the same from said locking dog by a treadle (not shown in the drawings but connected by a treadle rod 30 to a lever 31). The lever 31 is fast to a rock-shaft 32 (Figs. 2 and 3) which is journaled to rock in bearings in the base 11. An arm 33 is fastened to the rock-shaft 32 and engages a pin 34 in the tripper slide 25, whereby said slide is moved in the opposite direction to that in which it is moved by the spring 29.

15 The lever 31 is connected by a link 35 to a lever 36 pivoted at 37 to the base 11, the end of the horizontal arm of said lever projecting beneath the lower end of a treadle rod 38. The treadle rod 38 is adapted to slide in bearings 39 and 40 in the frame 10 and has fastened to its upper end a presser foot 41. The treadle rod 38 is encircled by a spring 42, the upper end of said spring adapted to bear against the lower face of the bearing 40, the lower end of said spring bearing against an arm 43 which is guided by a plate 44 fast to the frame 10.

30 The presser foot 41 normally rests upon the work-support 45 and may be raised or lowered by means of the treadle rod 30 acting through the lever 31, link 35 and lever 36, and during the automatic feeding and setting operation said presser foot is raised and lowered by means of a lever 46, one end 35 of which projects through a slot 47 in said treadle rod. The lever 46 is pivoted at 48 to the frame of the machine and is operated by a cam 49.

40 The mechanism for separating and feeding the lacing hooks and setting the same in the upper of the shoe forms no part of this invention but is fully shown and described in said Letters Patent. The upper is fed by a punch 50 which is fastened to a slide 45 51. This slide 51 is adapted to slide upon two horizontal rods 52. The rods 52 are fastened to a plunger 53 which is adapted to slide vertically in bearings 54 on the frame 10. A vertical motion is imparted to the plunger 53 by a rock-shaft 54', said rock-shaft having fastened to its forward end an arm 55 with a pin 56 fast thereto and projecting into a sliding block 57. The sliding block is located in a segmental slot 58 55 provided in a block 59 fast to the plunger 53.

60 A rocking motion is imparted to the shaft 54' by an arm 60 which is connected by a link 61 to a lever 62 pivoted at 63 to the frame 10, said lever having a rocking motion imparted thereto by a cam 64.

65 A horizontal motion is imparted to the punch 50 by a rock-shaft 65 to which an arm 66 is fastened, said arm having a pin 67 fast thereto and projecting into a sliding block 68. The sliding block 68 is free

to move vertically in a slot 69 formed in the slide 51. A rocking motion is imparted to the rock-shaft 65 by an arm 70 fast thereto and connected by a link 71 to a lever 72 pivoted on the rod 63 and having a rocking motion imparted thereto by the cam 73. Thus a vertical movement is imparted to the punch to move the same toward and away from the upper 94 and a horizontal movement is imparted to said punch in order that the same may feed the upper step by step and thus space the hooks the proper distance apart in said upper.

70 It is desirable in a machine of this class that the mechanism should be arranged so that the feed of the upper referred to can be varied so that lacing hooks may be spaced at different distances apart and it is also very desirable that this change in the length of feed of the upper shall be capable of being performed with ease and accuracy. Moreover, such a change in feed must be so arranged that the punch will always feed from the same point to a greater or less distance therefrom. To accomplish these results the link 71 is pivotally attached to the lever 72 at 74 and is adjustably fastened to the arm 70 in a manner now to be described. Said link is bifurcated at its upper end, thus terminating in two arms 75 and 76. A sleeve or bushing 77 is rigidly fastened to the arms 75 and 76 and has rotatably mounted thereon a sliding block 78. A locking pin 79 is mounted to slide longitudinally thereof within the sliding block 78 and has formed upon its front end a tooth 80, the crown 81 of which is in alignment with the median axial line *a* of the locking pin 79 (see Fig. 4). The rear end of the locking pin 79 is slotted at 82 to receive the end of a locking lever 83 which is pivoted at 84 to the link 71. A spring 85 holds the locking pin 79 normally in the position shown in Fig. 4.

75 The arm 70 is provided with a segmental slot 86 in which is located the sliding block 78. The tooth 80 on the locking pin 79 projects beyond the front face of the arm 75 and engages teeth 87 on a segmental plate 88, which plate is fastened by screws 89 to the arm 70. The opposite ends of the segmental plate 88 preferably rest upon forwardly extending portions 90 of the arm 70, thus leaving a slot 91 between the plate 88 and the front side of the arm 70 and within this slot 120 the outer end of the arm 75 projects.

80 The segmental slot 86 is concentric with the median axial line of the pivotal pin 74 when the slide 51 is located at the extreme right of its throw as viewed from the front 125 of the machine in Fig. 1. The slide is then in the position for the punch to begin its feed, that is the point to which it is necessary to bring the punch at the beginning of each feed, although the punch may be moved 130

to a greater or less extent from that starting point according to the position in which the locking pin 79 is placed relatively to the center of the rock-shaft 65. Both the crowns 5 and the bottoms of the teeth 87 are also preferably formed concentric with the median axial line of the pin 74 when the parts are in the position wherein the punch is just beginning to feed and it will be understood 10 that the crown 81 of the tooth 80, when the same engages any one of the teeth 87, is in alinement with the median axial line α of said locking pin 79.

A bracket 92 is fastened to the frame 10 of 15 the machine and said bracket has a horizontally extending arm 93 thereon which projects from the frame 10 transversely of the link 71 and adjacent to the locking pin lever 83 said arm is inclined transversely thereof 20 to a vertical plane and forms a rest for the hand of the operator, so that when it is desired to change the feed he can rest his hand upon this bracket arm 93 and press the locking pin lever 83 to move the pin 79 out of 25 engagement with the teeth 87 and move the pin along to any desired portion of the slot 86 while his hand rests firmly upon said bracket. When it is desired, therefore, to change the throw or extent of movement 30 imparted by the lever 72 to the arm 70 and thus, through the connecting parts, to change the feed of the punch laterally thereof, the operator moves the locking pin lever 83 by pressing the same toward the link 71, 35 thus moving the locking pin 79 out of engagement with the teeth 87 upon the plate 88 or, in effect, upon the arm 70 as said plate 86 is rigidly fastened to said arm. The operator then moves the link 71 to any desired 40 position and releases the locking pin lever 83 so that the locking pin 79 may engage any desired one of the teeth 87, these teeth being conveniently indexed upon the front side of the segmental plate 88 by means of suitable 45 letters or figures and by index lines running from the bottoms of the teeth along the front face of said plate, as shown in Fig. 3. Thus, it will be seen that as the link 71 is moved toward the right from the position shown in 50 Fig. 3 to engage the teeth at the right hand end of the segmental plate 88 the throw of the arm 70 will be decreased, while if said link is moved toward the left from the position shown in Fig. 3 to engage teeth nearer 55 the rock-shaft 65, the throw of the arm 70 will be increased. Moreover, it will be understood that as this change in position of the link 71 is made while the punch is at the extreme right of its movement or in the position 60 when it begins to feed the upper there will be no change in location of the arm 70 caused by this relative change in location of the link 71 thereto, on account of the segmental slot 86 being curved concentrically 65 with the median axial line of the pin 74

when the parts are in the relative positions hereinbefore set forth, so that the entire throw imparted to the part or parts connected to the arm 70 will be imparted by said arm from the position in which the 70 punch is at the extreme right or beginning of its throw to the position which it assumes at the other end of its throw and said part or parts connected to said arm will always be brought back to the same position at the 75 beginning of the throw, irrespective of the extent of said throw or feeding movement.

It will be understood that the operation of the machine of this invention, in order to be practical, must be very rapid and that to 80 change the throw of the punch, hereinbefore described, with ease and accuracy, without something to rest the hand upon, is very difficult if not impossible, as the operator would be liable to move the link several 85 teeth too far in one direction or the other, but by supplying the bracket 92, with its horizontally extending arm upon which to rest the hand of the operator while making this change, the operator is enabled to perform the adjustment of the link 71 relatively 90 to the arm 70 with ease and accuracy.

The general operation of the mechanism hereinbefore specifically described is as follows: The operator places the upper 94 to 95 have the lacing hooks set therein upon the work-support 45. At this time the presser foot is in its raised position. The operator then depresses the treadle, pulling downwardly upon the treadle rod 30 and rocking 100 the lever 31 so as to move the tripper slide 25 out of contact with the locking dog 24, thus throwing the clutch into operation, as hereinbefore described, and rotating the shaft 19. At the same time that this operation takes place the lever 36 is rocked, through the link 35, so as to lower the end of the lever which is in contact with the lower end of the rod 38, thus allowing the presser rod 38 and the presser foot 41 to descend and clamp the upper 94 to the work-support. The punch 50 then descends, punches a hole in the upper and feeds the same step by step the proper distance, according to the position of the locking pin 79 115 in the slot 86. At each feeding movement the presser foot 41 is raised and lowered automatically by the lever 46.

It will be seen that the movement whereby the presser foot is lowered into contact with the upper and the tripper slide 25 is operated to throw the clutch into operation are simultaneously performed by the single rod 30 and its treadle and that all of the working parts constituting the lacing hook setting mechanism are supported upon the frame 10, while the levers for operating the clutch slide and presser foot are mounted upon the base.

When it is desired to tip the organized 130

lacing hook setting mechanism with the frame 10 upon which it is mounted at an angle to the base 11 to allow the different parts of the mechanism to be readily accessible, the screws 13 and 14 are removed and the frame 10 with its organized lacing hook setting mechanism will then be free to be tipped upon the pivot 12.

Having thus described my invention, what I claim and desire by Letters Patent to secure is:

1. A lacing hook setting machine having, in combination, a slide, vertical ways for said slide, mechanism adapted to impart a vertical motion to said slide, another slide mounted to slide horizontally on said vertically movable slide, a punch fast to said horizontal slide, mechanism adapted to move said horizontal slide embodying two levers and a link connecting said levers together, said link being pivoted to one of said levers, and adjustable means mounted on said link adapted to pivotally connect the other end of said link to the other of said levers at different distances from the axial center of said last-named lever.

2. A lacing hook setting machine having, in combination, a slide, vertical ways for said slide, mechanism adapted to impart a vertical motion to said slide, another slide mounted to slide horizontally on said vertically movable slide, a punch fast to said horizontal slide, mechanism adapted to move said horizontal slide embodying a shaft, a cam fast thereto and two levers having the median axial lines of their fulcrums substantially parallel to the median axial line of said shaft and a link connecting said levers together, a locking pin mounted on said link to slide transversely thereof and pivotally connecting one of said levers and said link together, said last-named lever having a segmental slot therein, a series of teeth on said last-named lever concentric with said segmental slot and a tooth on said locking pin adapted to engage the teeth on said lever, said locking pin adapted to be moved longitudinally thereof into and out of engagement with the teeth on said lever.

3. A lacing hook setting machine having, in combination, a slide, vertical ways for said slide, mechanism adapted to impart a vertical motion to said slide, another slide mounted to slide horizontally on said vertically movable slide, a punch fast to said horizontal slide, mechanism adapted to move said horizontal slide embodying a shaft, a cam fast thereto and two levers having the median axial lines of their fulcrums substantially parallel to the median axial line of said shaft and a link connecting said levers together, a locking pin mounted on said link to slide transversely thereof and pivotally connecting one of said levers and

said link together, said last-named lever having a segmental slot therein, a series of teeth on said lever concentric with said segmental slot, a tooth on said locking pin adapted to engage the teeth on said lever and a locking pin lever pivoted to said link and engaging said locking pin adapted to move the same longitudinally thereof into and out of engagement with the teeth on said lever.

4. A lacing hook setting machine having, in combination, a slide, vertical ways for said slide, mechanism adapted to impart a vertical motion to said slide, another slide mounted to slide horizontally on said vertically movable slide, a punch fast to said horizontal slide, mechanism adapted to move said horizontal slide embodying a shaft, a cam fast thereto and two levers having the median axial lines of their fulcrum substantially parallel to the median axial line of said shaft and a link connecting said levers together, a locking pin pivotally connecting one of said levers and said link together, said last-named lever having a segmental slot therein, a series of teeth on said lever concentric with said segmental slot, a tooth on said locking pin adapted to engage the teeth on said lever, a locking pin lever pivoted to said link and engaging said locking pin adapted to move the same longitudinally thereof into and out of engagement with the teeth on said lever and a spring adapted to hold said locking pin in engagement with said teeth.

5. An organized lacing hook setting machine embodying a frame, a driving shaft journaled on said frame, a pulley loosely mounted on said shaft, a clutch adapted to lock said pulley to said shaft, a base on which said frame is hinged and manually operable mechanism mounted on said base having detachable engagement with said clutch mechanism and adapted to operate said clutch mechanism to lock said pulley to said shaft and to unlock said pulley from said shaft.

6. An organized lacing hook setting machine embodying a frame, a work-support, a presser foot, a presser foot rod fast to said presser foot and slidable on said frame, a base on which said frame is hinged, and manually operable means mounted on said base adapted to engage said rod and move said presser foot away from said work-support.

7. An organized lacing hook setting machine embodying a frame, a driving shaft, a pulley journaled on said driving shaft, clutch mechanism adapted to lock said pulley to said shaft, a work-support, a presser foot, a presser foot rod fast to said presser foot and slidable vertically on said frame, a base on which said frame is hinged

and manually operable mechanism mounted on said base having detachable engagement with said clutch mechanism and adapted to operate said clutch mechanism to lock said pulley to said shaft, said manually operable mechanism being adapted to detachably engage said rod and move said presser foot away from said work-support.

In testimony whereof I have hereunto set my hand in presence of two subscribing witnesses.

ARTHUR R. HAVENER.
